(57) **CLAIM**

The ornamental design for a combined cookware handle and utensil rest, as shown and described.

DESCRIPTION

FIG. 1 is a front perspective view of the first embodiment of a combined cookware handle and utensil rest shown in an environment of use;

FIG. 2 is a front view thereof;

FIG. 3 is a left view thereof;

FIG. 4 is a right view thereof;

FIG. 5 is a top view thereof;

FIG. 6 is a perspective view of the second embodiment of a combined cookware handle and utensil rest shown in an environment of use;

FIG. 7 is a front view thereof;

FIG. 8 is a left view thereof;

FIG. 9 is a right view thereof;

FIG. 10 is a top view thereof;

FIG. 11 is a bottom view of the combined cookware handle and utensil rest shown in an alternate environment of use;

FIG. 12 is an exploded front view of the combined cookware handle and utensil rest shown in an environment of use;

FIG. 13 is a left view thereof; and,

FIG. 14 is a right view thereof.

The broken lines shown in the drawings represent environment and form no part of the claimed design.
